DESIGN FOR AN AUTOMOBILE OR SIMILAR ARTICLE

John Lagana, Scarsdale, N. Y.

Application March 22, 1941, Serial No. 99,775

Term of patent 7 years

To all whom it may concern:

Be it known that I, John Lagana, a citizen of the United States of America and a resident of Scarsdale, in the county of Westchester, State of New York, have invented a new, original, and ornamental Design for an Automobile or Similar Article, of which the following is a specification, reference being had to the accompanying drawing, forming part thereof.

Fig. 1 is a side elevation of an automobile showing my new design;

Fig. 2 is a front elevation of an automobile showing my new design;

Fig. 3 is a rear elevation of an automobile showing my new design.

It is to be understood that the design may be applied to any vehicle, whether it is the size of a miniature, a toy, or a full-size vehicle.

I claim:

The ornamental design for an automobile or similar article, substantially as shown and described.

JOHN LAGANA.
